UNITED STATES PATENT OFFICE.

ORIN BENNETT, OF SAN FRANCISCO, CALIFORNIA.

COMBINATION LOCK.

Application filed April 26, 1924. Serial No. 709,156.

To all whom it may concern:

Be it known that I, ORIN BENNETT, a citizen of the United States, residing at the city and county of San Francisco and State of California, have invented certain new and useful Improvements in Combination Locks, of which the following is a specification.

This invention relates to a door latch and lock of what may be termed the combination type i. e. of the type adapted to be released on the operation of a certain predetermined combination rather than by the use of a key.

Among the objects of the invention is to provide a door lock of the combination type in which the bolt thereof is released for movement due to the operation in their proper order of tumbler actuating devices, and is automatically held from releasing movement immediately on the operation of a tumbler operating device out of its sequential order.

A further object is to provide a bolt locking member which is normally held in bolt locking position by the actuation of a spring and which is released on the correct sequential operation of the tumbler actuating devices.

Another object is to provide an improved form of knob shaft construction whereby the connection between one knob and the bolt throwing mechanism may be interrupted when desired.

A further object is to provide a lock adapted for hotels, lodging and rooming houses and the like whereby in its use keys are dispensed with and the room occupant operates the lock solely by working the correct combination, and to provide a lock for this use wherein the combination can be quickly changed without material effort.

With the above mentioned and other objects in view, the invention consists in the novel construction and combination of parts hereinafter described, illustrated in the accompanying drawings, and set forth in the claims hereto appended, it being understood that various changes in the form, proportion, size and minor details of construction within the scope of the claims may be resorted to without departing from the spirit or sacrificing any of the advantages of the invention.

To more fully comprehend the invention reference is directed to the accompanying drawings, wherein:

55

Figure 1 is a view in side elevation of the preferred embodiment of my invention.

60

Figure 2 is a vertical sectional view taken directly inside of the face plate on line 2—2 of Figure 3, illustrating the relative position of the parts forming the interior mechanism.

Figure 3 is a transverse sectional view on line 3—3 of Figure 2.

65

Figure 4 is a similar view on line 4—4 of Figure 2.

65

Figure 5 is a view in detail plan of the knob shaft construction.

Figure 6 is a sectional view on line 6—6 of Figure 5, and

70

Figure 7 is a similar view on line 7—7 of Figure 5.

Figure 8 is a vertical sectional view taken on line 8—8 of Figure 2 viewed in the direction of the arrows.

75

Figure 9 is a view in detail of the tumbler shaft operating spring.

Figure 10 is a view on line 10 of Figure 8 illustrating one of the tumbler notches in position to be engaged by its operating means.

80

Figure 11 is a view on line 11 Figure 8 illustrating the tumbler in a position so that its operating means will ride on its periphery and release the shaft retaining pawl.

80

Figure 12 is a sectional view on line 12—12 of Figure 8 illustrating the pawl and ratchet mechanism.

85

In the drawings wherein like characters of reference designate corresponding parts, the numeral 1 indicates a lock casing preferably of rectangular configuration and mounted thereon for reciprocating movement is a latch bolt 2, the forward end of which projects from one edge of the casing through an opening 3 and is bevelled to form a latch as at 4. The spring 5 bearing against the flange 6 and anchored within the casing as at 7 normally tends to project said bolt through its opening 3. The bolt is notched as at 8 to receive an arm 9 extending radially from a tubular shaft 10 rotatably mounted at its ends within and extending through openings 11 in the lock casing 1. The shaft 10 has mounted therein

90

95

100

a solid shaft 12 cross grooved at one end as at 13, and at its opposite end mounting a knob or other operating device not shown. Extending into the tubular shaft 10 from its opposite end is a second solid shaft 14 keyed as at 15 for longitudinal movement within the shaft 10 which admits through the slot 16 of longitudinal movement of the solid shaft 14. The shaft carries at its end 10 a projection 17 for engagement within one of the grooves 13 as illustrated in Figure 5. The shaft 14 carries a knob 18 for imparting axial rotation thereto and this shaft construction enables the separation of the 15 shafts and the operation of the member 9 by the rotation of but one knob. The members for retaining the member 2 normally in locked position consists of a cam 19, the arcuate surface 20 of which is adapted for 20 normal reception within a corresponding cut out or groove 21 in one face or surface of the member 2 within the casing 1.

The cam 19 is adjustably mounted on a shaft 22, the latter being rotatably mounted 25 at its ends in bearings 23, in opposite walls of the casing 1, the shaft being illustrated as disposed at right angles to the knob shaft 10. The shaft 22 throughout its length mounts a plurality of tumbler disks 24 30 each formed in its periphery with one or more notches 25, and each held in its adjusted position on the shaft 22 by a set screw 26. This adjustment of each tumbler independent of the other about the shaft 22 35 enables the relative setting of the notches of the respective tumblers radially about the shaft in any desired position.

Extending parallel of the shaft 22 is a pawl frame 27 fulcrumed at its ends as at 40 28 for swinging movement, and the same carries an adjustable pawl 29 adapted to engage the teeth 30 of a ratchet 31 mounted on the shaft 22 between adjacent tumblers 24. A spring 32 normally forces the pawl 45 29 within the path of the teeth 30.

The combination mechanism for the lock consists in a plurality of plungers operated from the exterior of the lock casing 1, and one cooperating with each tumbler 24, in 50 the present embodiment there being five tumblers and consequently five plungers. Each plunger being a duplicate of the other, a description of one is thought will suffice. Mounted in a tubular guide 33 extending

55 through one wall of the lock casing 1 at right angles to shaft 22 and slightly offset therefrom at a point to lie opposite a tumbler, is mounted to reciprocate a plunger 34 formed at its outer end with an enlarged head 35. The plunger is slotted as at 36 and a pin 27 passes therethrough and through the guide 33 to retain the plunger within the guide, the pin also forming a stop for one end of a coiled spring 38, the tendency 60 65 of which is to normally maintain the

plunger outwardly projected in the guide 33. The inner end of the plunger mounts on a pin 39 disposed in a plane parallel with the shaft 22, the inner end of a pawl 40. The outer end of the pawl is pointed as at 70 41 and is adapted for pivotal movement as the pawl swings about the pin 39.

Referring to Figure 10, it will be observed that when the tumbler 24 is in the position with one of its notches 25 lying opposite the end of the pawl 40 that an inward movement of the pawl 40 by pressure on plunger 44 will cause the pawl to engage within the notch 25 and impart a rotation to the shaft 22 against the tension of a shaft resisting 80 spring hereinafter described. The shaft 22 is held in its operative position by the member 29 engaging with one of the teeth 30. During this operation it will be observed that the pawl 40 does not engage the frame 85 27.

Now referring to Figure 11, it will be observed that with the tumbler 24 in the position illustrated an inward movement of the plunger 34 will cause the pawl 40 to ride on the periphery 40' of the tumbler and be forced into contact with the frame 27, which action would withdraw the member 29 from engagement with the teeth 30, and the action of the spring hereinafter described 95 would return the shaft 22 to normal position.

A shaft return spring 41 is secured at one end as at 42 to the shaft 22 and at its opposite end as at 43 to the casing 1, the action of the spring being to normally maintain the cam 20 within the depression 21 should for any reason due to the operation of one of the plungers 34 the pawl 29 be released from engagement with its co-operating teeth 30.

It will be observed that the tumblers being positioned as desired on the shaft 22 with their notches 25 lying in any relative desired relation, a predetermined sequential operation of the plungers 34 is required to impart the desired rotation to the shaft 22 to remove the cam 19 from recess 21, and it will also be apparent that the incorrect operation of the plungers, i. e. the operation of a plunger at a time when a notch is not in register with the end of its lever 40, will cause the release of the retaining member 29 and enable the spring 41 to return the shaft 22 to what may be termed "locking position."

Having thus described my invention what I claim as new and desire to secure by Letters Patent of the United States is:—

1. A combination lock including rotating tumblers having notched peripheries, a sliding bolt, a member movable with the tumblers for locking engagement with the bolt to preclude operative movement of the latter, reciprocating tumbler operating devices one co-operating with each tumbler for operative engagement with the notched periphery of its co-operating tumbler, spring means asso- 120 125 130

ciated with the tumblers for normally returning the same to a predetermined position, a pawl and ratchet mechanism co-operating with the tumblers for retaining the same in their operated position, said mechanism movable to released position on the operation of one of the tumbler operating devices when the notch of its associated tumbler is out of register with the operating device.

2. A combination lock including a rotating tumbler shaft, a slide bolt and a rotating knob shaft arranged with their axes in angular relation, tumblers carried by the tumbler shaft and formed with notched peripheries, a member carried by the tumbler shaft for locking engagement with the sliding bolt to preclude operative movement of the latter,

a connection between the knob shaft and the sliding bolt whereby the same is operative on the release of said locking member, a plurality of tumbler operating devices one co-operating with each tumbler for operative engagement with the notched peripheries thereof, a spring associated with the tumbler shaft for resisting the rotation of the same by the tumbler operating devices, a pawl for retaining the shaft in its rotated position, said pawl adapted for movement to releasing position by the actuation of one of said tumbler operating devices and out of register with the notch of the pawl.

In testimony whereof I have signed my name to this specification.

ORIN BENNETT.
